UNITED STATES PATENT OFFICE

HENRY M. YEAGER, OF BUFFALO, NEW YORK, ASSIGNOR TO FEEDERS MANUFACTURING COMPANY, INC., OF BUFFALO, NEW YORK, A CORPORATION OF NEW YORK

MOUNTING FOR RADIATORS

Application filed July 17, 1926. Serial No. 123,076.

This invention relates to a mounting for the radiator of motor vehicles and more particularly trucks in which the radiators are subjected to very heavy vibrations and 5 shocks.

It is the object of this invention to provide a mounting for this purpose whereby any weaving or vibration in the main frame or chassis of the car will not be transmitted 10 to the radiator and cause leakage in the latter; also to provide a mounting for radiators which permits of quickly assembling the parts for use and disassembling the same for 15 repairs; also to permit of taking down and putting up the parts for effecting repairs without destroying any parts of the radiator or mounting and without requiring the replacement of any parts.

In the accompanying drawings:

20 Figure 1 is a front elevation of a radiator mounted in accordance with my invention;

Figure 2 is a side elevation of the same;

Figure 3 is a vertical longitudinal section, on an enlarged scale, of my improved radiator mounting applied to a radiator and casting or shell;

Figures 4 and 5 are fragmentary vertical cross-sections, on an enlarged scale, taken on the correspondingly numbered lines in Figure 1;

30 Figure 6 is a fragmentary bottom view of the shell showing the manner of attaching the lower part of the radiator thereto;

Figure 7 is a similar view, partly in section, 35 showing the radiator removed therefrom;

Figure 8 is a fragmentary rear elevation of the shell and stud for showing the manner of detachably connecting the same.

Similar characters of reference indicate 40 like parts in the several figures.

The radiator may be of any suitable and well known construction that, for example, which is shown in the drawings, consisting of a central cellular core 10 provided with a plurality of water passages and a plurality of air passages intercalated with said water passages, an upper water tank or box 11 which communicates on its underside with the upper ends of said water passages and a lower water 45 tank or box 12 which communicates on its

upper side with the lower ends of said water passages. On the central part of the upper water tank the same is provided with an inlet nipple 13 and one of the lower corners of the lower water tank is provided with an outlet nipple 14, which nipples are adapted to be connected with the water circulating system of the gas engine which serves as the power unit for driving the auto. Projecting upwardly from the central parts of the top of the upper tank is an upright filling neck 15 through which water is introduced into the radiator for replenishing the same when necessary and which is normally closed at its upper end by a filler cap 16 having a screw 50 connection therewith.

The shell or housing which is adapted to receive the radiator for enclosing and protecting the same comprises a horizontal bottom 17, two upright side walls 18, 19 rising from the opposite ends of the bottom, an upwardly bowed top 20 connecting the upper ends of the side walls, flanges 21, 22, 22, 23 projecting inwardly from the bottom, side walls and top of the shell, and supporting lugs 24 projecting laterally from the side walls 18, 19 and adapted to be detachably secured by bolts 60 or otherwise to the longitudinal bars 25 of the frame forming parts of the chassis 55 of the car. The parts of the shell just described are preferably formed integrally by casting of metal such as aluminum.

The improved means for removably mounting the radiator within this shell in accordance with my invention are constructed as 60 follows:

Arranged horizontally and lengthwise below the lower water tank is a stud bar 26 which is provided at its opposite ends with upwardly projecting arms 27, 27, arranged alongside of the ends of the lower water tank and the lower end parts of the core. On its upper side the stud bar is provided with a lower channel shaped retaining clip which receives the central part of the lower water 65 tank and which has its horizontal web 28 spot welded to the top of the stud bar and its upright flanges 29 soldered to the front and rear walls of the lower tank. In order 70 to avoid any squeaks in the joint between the 75

stud bar and the radiator due to vibration when the car is running a strip 30 of canvas or other anti-squeak material is placed between the underside of the lower tank and the top of the web 28 of the lower retaining clip. Each of the arms of the stud bar carries an upright side clip or side wall which has a web 31 secured by spot welding to the inner side of the respective stud bar arm and two inwardly projecting flanges 32, 32 which embrace the adjacent upright edge portion of the core. Secured to opposite ends of the upper tank and extending downwardly along opposite upper edge portions of the core are two metal straps 33, 33 which are connected with the upper tank by soldering and detachably connected with the side walls or clips by bolts 34 passing through laterally extending flanges 35 arranged on the upper ends of the webs 31 and the lower ends of the straps, as shown in Fig. 3. Each of the straps is preferably provided with a few corrugations 36 in order to render the same somewhat elastic and permit the same to yield when subjected to strain. Between the underside of the stud bar and the bottom of the shell is arranged an anti-squeak pad 37 of woven fabric, canvas or the like which effectively cushions the parts relatively to each other and prevents any squeaking noise due to shifting of parts relatively to one another when the car is in operation. The stud bar is detachably connected with the bottom of the shell by two fastenings which are arranged on opposite sides of the center of the radiator and as these fastenings are alike in construction the following description of one will apply to both.

Extending forwardly from the rear edge of the bottom of the shell is a horizontal slot 38 the closed front end of which is surrounded by an upwardly extending counter sunk seat 39 which is preferably of circular form. For the purpose of straightening this slotted part of the shell bottom a downwardly deflected bridge 40 preferably connects those parts of the shell bottom on opposite sides of the rear or open end of the slot 38. Projecting downwardly from the stud bar is a stud bolt 41 which has its upper headed end preferably brazed or welded to the bar while its lower threaded end passes through the anti-squeak pad 37 and through the slot 38 in the shell bottom at the front end thereof. The stud bar is securely held against vertical and horizontal displacement on the shell bottom by a retaining ring 42 surrounding the stud bolt and engaging with the counter sunk seat 39, a split spring or lock washer 43 engaging with the underside of the retaining washer, and a clamping screw nut 44 applied to said stud bolt 41 and bearing against the underside of the lock washer. When both of these fastening means are thus applied to the lower part of the radiator core and the bottom of

the shell the radiator is not only held firmly against the bottom but also prevented from moving horizontally inasmuch as the retaining ring 42 which engages the counter sunk seat 39 prevents such movement. When however it is desired to remove the radiator from the shell it is only necessary to slacken the clamping nuts 44 enough to permit the retaining rings to drop out of the seats 39 after which the stud bolts and the rings, washers and nuts mounted thereon may be moved rearwardly out of slot 38 and through the bridges 40 while the lower part of the radiator and parts connected therewith are removed rearwardly from the corresponding part of the shell.

On the central part of the top of the shell the same is provided with an upwardly projecting tubular neck 45 which receives the filling tube 15 of the radiator. A cushioned joint is formed between this neck and the filling tube by an elastic grommet or ring 46 surrounding the filling tube within the neck and bearing with its conical underside 461 against an upwardly facing conical shoulder 47 on the interior of the neck, and a clamping ring 48 having a screw connection with said neck and bearing with its lower conical end 49 against the upper conical side 50 of the grommet, whereby the latter is compressed and caused to fit tightly between the filling tube and neck and prevent the same from rattling when the car is in motion.

When assembling the radiator and the shell the upper part of the radiator is first moved forwardly into the upper part of the shell and then moved upwardly so as to pass the filling tube through the tubular neck from the inner to the outer end thereof and at the same time the lower part of the radiator and associated parts are moved forwardly into the lower part of the casing and the stud bolts are moved forwardly into the slots 38. The screw nuts 44 are now tightened so as to force the retaining rings 42 into their seats and draw the stud bar down against the anti-squeak pad on the bottom of the shell. The grommet is also slipped over the filling tube and forced downwardly between the same and the tubular neck by applying the clamping ring 48 to the neck and producing a tight fit between the grommet, neck and filler tube.

When thus assembled the radiator is supported at practically three points on the shell, that is to say, by the two stud bolts near opposite ends of its lower part and by the filling tube on the central upper part thereof, while the remaining parts of the radiator are out of engagement with the shell. Due to this mounting of the radiator, any weaving action or strains to which the shell may be subjected while in use will not be transmitted to the radiator inasmuch as the filling tube of the radiator will slide lengthwise in the neck during any relative movement of the shell and

radiator, thereby preventing any leaks in the latter and avoiding the necessity of frequent repairs. If, however, any extensive repairs of the radiator become necessary at any time which requires the removal of the radiator from the shell this can be easily accomplished by simply loosening the clamping nuts 44 on the stud bolts and removing the clamping ring from the tubular neck, when the parts may be readily dismembered. It is, therefore, possible to readily remove the radiator from the shell and restore the same without destroying any parts or making any replacements while effecting such removal out of and restoration of the core into the shell.

The diameter of each seat 39 and the retaining ring 42 seated therein is larger than the width of the slot 38 which accounts for this ring and the stud bolt 41 within this ring not being locked in position on the bottom of the shell when the screw nuts 44 are tightened.

I claim:

1. A shell having a bottom, provided with an open-ended slot extending forwardly from the rear edge thereof, a radiator arranged within the shell, and a stud bolt mounted on the lower end of said radiator and arranged within said slot and provided with a clamping nut adapted to press toward the underside of said bottom.

2. A shell having a bottom, provided with a slot extending forwardly from the rear edge thereof and a downwardly extending bridge connecting the parts of said bottom on opposite sides of the rear part of said slot, a radiator arranged within the shell, and a stud bolt mounted on the lower end of said radiator and arranged within said slot and provided with a clamping nut adapted to press toward the underside of said bottom.

3. A shell having a bottom provided with a slot extending forwardly from the rear edge of the bottom and a countersunk seat arranged around the underside of the front end of said slot, a radiator arranged within the shell, a stud bolt mounted on the underside of said radiator and projecting downwardly therefrom through the front end of said slot, a retaining ring surrounding said bolt and engaging said seat and a screw nut applied to said bolt and adapted to press upwardly toward said ring.

4. A shell having a bottom provided with a slot extending forwardly from the rear edge of the bottom and a counter sunk seat arranged around the underside of the front end of said slot, a radiator arranged within the shell, a stud bolt mounted on the underside of said radiator and projecting downwardly therefrom through the front end of said slot, a retaining ring surrounding said bolt and engaging said seat, a screw nut applied to said bolt and adapted to press upwardly toward said ring and a lock washer

interposed between said screw nut and said ring.

5. A shell having a bottom, a radiator arranged within said shell, a bar connected with the underside of said radiator and detachably connected with said bottom, arms projecting upwardly from the ends of said bar on opposite sides of said radiator, and means for detachably connecting the upper ends of said arms with the top of said radiator comprising U-shaped clips having webs secured to said arms, inwardly projecting flanges embracing the sides of said radiator and outwardly projecting lugs at the upper ends of said webs, straps connected at their upper ends with the top of the radiator and provided at their lower ends with laterally projecting lugs and intermediate of their ends with corrugations, and coupling bolts connecting the corresponding lugs of said straps and webs.

6. In a radiator, the combination with an integral casing having an apertured front face and top and bottom wall flanges extending rearwardly therefrom, the top wall flange having a filler opening therethrough, the bottom wall flange comprising a slotted portion, a radiator core comprising an upwardly extending tubular filler neck at its top and a stud extending downwardly from its bottom wall, said core neck being of such smaller outer diameter than the bore of the opening to permit insertion of the neck through the bore from the rear thereof when angularly projected upwardly therethrough, the casing being opened at its rear bottom portion so as to permit forwardly advancing the bottom of the core to a position directly below the casing top wall, with the said stud projected within the bottom wall slot, and clamping means to removably secure the core in inserted position within the casing.

7. In a radiator, the combination with an integral casing having an apertured front face and top and bottom wall flanges extending rearwardly therefrom, an upwardly projecting extension for the top wall flange having a tubular filler opening therethrough, a radiator core comprising an upwardly extending tubular filler neck at its top, means to secure the bottom of the core to the casing bottom wall flange comprising a key element of the one adapted to be projected within a slot of the other, said core neck being of such smaller outer diameter than the bore of the opening to permit insertion of the neck through the bore from the rear thereof when angularly projected upwardly therethrough, the casing being opened at its rear bottom portion so as to permit forwardly advancing the bottom of the core to a position directly below the casing top wall with the said key element projected within the said slot, and clamping means to removably secure the core in inserted position within the casing.

8. A radiator comprising a casing having an opening, a core within the casing and provided with a filler slidable in said opening, the casing having an open-ended slot and the core having a stud slidably engageable in said slot through its open end, and means for clamping the stud in the slot to detachably secure the core within the casing.

9. In a radiator, the combination with a casing having top, bottom and side walls and a filler opening in its top wall, a radiator core within the casing, said core having a filler neck extending through said opening, and means for detachably securing the core to the casing, said securing means comprising a stud and a slotted member, one on the bottom of the core and the other on the bottom portion of the casing, the stud being engageable in the slot of said slotted member, and a clamping member adapted to clamp said stud and slotted member together.

10. A radiator comprising a casing having an opening, a core within the casing having a projection on its top portion loosely extending into the opening, and permitting the radiator to be moved into the casing about the projection as a pivot, the bottom of the casing having an open-ended slot, the bottom of the core being provided with a stud engageable in the slot through its open end by moving the casing about the projection as a pivot, and means for clamping the stud in said slot to detachably secure the core in the casing.

35 11. A radiator comprising a casing having an opening, a core within the casing and provided with a filler slidable in said opening, the casing having an open-ended slot and the core having a stud slidably engageable in said slot, and means for clamping the stud in said slot for detachably securing the core within the casing.

In testimony whereof I affix my signature.
HENRY M. YEAGER.
